UNITED STATES PATENT OFFICE

CLIFTON E. SWEENEY, OF INDIANAPOLIS, INDIANA

RIVETING IRON

Application filed October 10, 1929. Serial No. 398,716.

The present invention relates to riveting irons and the like and more particularly to riveting irons adapted for use in combination with an air-driven riveting hammer.

An object of this invention is to provide a riveting iron of this character which may be adapted for use in constructions where the use of a hot rivet is impossible and particularly where a metal frame or the like is to be riveted to a wooden or other combustible structure.

Another object of this invention is to provide a device of this character which is readily transported or moved from point to point, being of sufficient lightness in weight to make the device practical for use in structures where the present riveting iron is exceedingly cumbersome and difficult to use.

A further object of this invention is to provide a device of this character wherein means are provided in the base of the device for securely holding the same in adjusted position.

The above and various other objects and advantages of this invention will in part be understood from and in part described in the following detailed description of the present preferred embodiment, the same being illustrated in the accompanying drawing

30 wherein:—

Fig. 1 is a sectional view of a riveting iron constructed according to the present invention removably mounted on a beam, also shown in cross section.

35 Fig. 2 is a plan view of the device.

Fig. 3 is a plan view of the cam.

Fig. 4 is a sectional view taken on the line 4—4 of Fig. 3.

40 Fig. 5 is a fragmentary plan view of the forward end of the handle.

Referring to the drawing, the numeral 10 designates a section of framework or beam which is secured to a floor structure 11 or the like by the rivets 12 which have their heads 45 13 countersunk in the wood 11, and the lower end 14 of the rivet 12 is formed into the shape of a normal rivet head 14 which bears against an inwardly extending flange 15 which is secured to the frame 10 by rivets 16 or the like.

50 A base 17 for a riveting iron is provided

with a plurality of slots 18 which preferably extend in horizontal relation to the base, and a sleeve 19 or the like is mounted in a substantially vertical position on the base. It will, of course, be understood that the base 55 17 and the sleeve 19 may be constructed of any suitable material but preferably of metal or the like, and may be formed as a unit.

A shaft 20 is slidably mounted in the sleeve 19 and is adapted at its lower end to protrude from the lower end of the sleeve and extend upwardly from the upward end of the sleeve. The upper end of the shaft 20 is provided with a rivet setting tool 21 or the like which may be of any suitable configuration so as 60 65 to produce the desired shape of the head 14 of the rivet.

A cam 22 is pivotally mounted on the base 17 and a handle 23 is secured to said cam and extends outwardly of the base so that 70 the cam may be turned upon its pivot 24. The lower end of the shaft 20 is angularly inclined as at 25 so as to conform to the configuration of the cam and to bear against the inclined surface of the cam when it is 75 moved on its pivot.

In the operation of this device, the base 17 is preferably removably mounted in the frame 10 in a substantially vertical position so that the rivet setting member 21 is in 80 alignment with the rivet 14 which it is desired to secure in position. The cam 22 is turned on its pivot 24 by means of the handle 23 so as to move the shaft 20 upwardly and engage the rivet 12. An air riveting ham-

85 mer or the like is adapted to bear against the upper end of the rivet and by striking the upper end of the rivet, the lower end thereof is turned over to conform to the configuration of the rivet setting tool and thereby firmly engages flange 15 against the wooden structure 11. As the lower end of the rivet 12 is gradually turned over, the handle 23 is moved horizontally so as to turn the cam on its pivot and force the shaft 20 upwardly to constantly bear against the lower end of the rivet.

90 95 The cam 22 may be provided with an opening 26, which in the present preferred embodiment is preferably square, and the for-

ward end of the handle is provided with a downwardly extending sleeve portion 27 adapted to engage in the square opening 26 of the cam. An anti-friction sleeve element 5 28 is loosely mounted in the opening 29 in the forward end of the handle 23. The pivot 24 extends downwardly through the opening 29 and is secured to the base 17 by a nut 30 or the like.

10 It will, of course, be understood that various changes and modifications may be made in the details of construction and design of the above specifically described embodiment of the invention without departing from the 15 spirit thereof, such changes and modifications being restricted only by the scope of the following claims.

I claim:—

1. A riveting iron comprising a base, said 20 base having a plurality of grooves, a sleeve upstanding from said base, a shaft slidably mounted in said sleeve and in said base, a rivet head mounted on said shaft on the upper end thereof, the lower end of said 25 shaft being inclined with respect to the longitudinal axis thereof, a cam pivotally mounted on said base and engaging said lower end of said shaft, and means for turning said cam whereby to move the shaft upwardly.

2. A riveting iron comprising a base, said 30 base having a plurality of horizontally arranged grooves, a shaft mounted on said base for vertical movement therein, said 35 shaft being mounted on said base in offset relation to said grooves, rivet setting means on said shaft and adapted for movement therewith, and cam means pivotally mounted on said base and engaging the shaft.

3. A riveting iron comprising a base, said 40 base having a plurality of grooves, a sleeve mounted on the base in offset relation to the grooved portion of the base and extending upwardly therefrom, a shaft slidably mounted in the sleeve, rivet setting means mounted on the outer end of said shaft, cam means pivotally mounted on the base and adapted for horizontal rotation thereon, the lower end of said shaft being angularly inclined 45 so as to bear against the inclined surface of said cam and means for turning the cam on its pivot whereby to move the shaft upwardly.

4. A riveting iron comprising a grooved 55 base, a shaft slidably mounted in said base and offset from said grooved portion of said base, rivet setting means on the outer end of said shaft and operating means engaging the lower end of said shaft.

5. A riveting iron comprising a base, said 60 base having a plurality of grooves therein, a sleeve upstanding from said base and positioned in offset relation to the grooved portion, a shaft slidably mounted in said sleeve, 65 rivet setting means mounted on the outer

end of said shaft and operating means engaging the lower end of said shaft whereby to move the same upwardly in the sleeve, said operating means comprising a cam pivotally mounted on the base, and means for turning the cam on its pivot, the lower end 70 of said shaft being angularly inclined to engage the inclined surface of the cam.

In testimony whereof I hereunto affix my signature.

CLIFTON E. SWEENEY.
